UNITED STATES PATENT OFFICE.

LAURITZ W. ANDERSEN, OF WATERBURY, CONNECTICUT, ASSIGNOR TO THE PLUME & ATWOOD MANUFACTURING COMPANY, OF WATERBURY, CONNECTICUT, A CORPORATION OF CONNECTICUT.

SCREWLESS SOCKET-COVER AND HOLDER.

1,096,523.

Specification of Letters Patent. Patented May 12, 1914.

Application filed March 22, 1913. Serial No. 756,193.

To all whom it may concern:

Be it known that I, LAURITZ W. ANDERSEN, a citizen of the United States, residing at Waterbury, in the county of New Haven and State of Connecticut, have invented a new and useful Improvement in Screwless Socket-Covers and Holders, of which the following is a specification.

This invention relates generally to electric light fixtures and more particularly to a combined socket cover and shade holder.

The form of socket cover and holder herein shown and described is particularly adapted for closed glassware but it will of course be understood that it can be used equally as well upon other forms of shades or globes.

The principal object of my invention is to provide a screwless socket cover and holder, as heretofore screws have usually been employed in connection with the socket cover and holder for the purpose of connecting and supporting the shade. My invention completely avoids the use of such screws and embodies an exceedingly simple, durable and efficient device for receiving and holding the incandescent light, socket and shade or globe surrounding the same.

Another object of the invention is to provide a device which shall not only be simple and efficient, but which will also readily lend itself to various schemes of ornamentation.

With these various objects in view, my invention consists essentially in the employment of an inner shell adapted to receive and hold a lamp socket, said inner shell having hinged wings or other shade engaging means adapted to be inserted into the mouth of the shade to engage the interior thereof, said inner shell having an outer shell movable thereon and preferably connected thereto by threads, said outer shell being adapted to engage the exterior of the globe or shade and simultaneously lock the interior engaging wings in their proper positions, thereby securely clamping the globe or shade between said wings and outer shell and completely avoiding the use of fastening screws to secure the globe or shade.

The invention consists also in certain details of construction hereinafter fully described and pointed out in the claims.

In the drawings forming a part of this

specification: Figure 1 is a view showing the practical application of my invention, the globe or shade being securely fastened to the combined screwless socket cover and holder. Fig. 2 is a view showing the manner of connecting or disconnecting the several parts, the outer shell being raised to permit the hinged wings to be collapsed so as to permit their insertion or withdrawal from the mouth of the glassware which may be in the form of a globe or other shape of shade. Fig. 3 is a vertical sectional view of the complete device, the lamp socket and lamp being shown in elevation. Fig. 4 is a detail view of the inner shell and a portion of one of the hinged wings, this view illustrating the manner of hinging the said wings to the inner shell. Fig. 5 is a top plan view of an inner shell having there wings hinged thereto.

Referring to the drawings A, indicates a glass globe or shade, B, the incandescent lamp and C the socket, all of which are of the usual or any improved construction. It will be understood that although I have shown the shade A, globular in form my invention can be used equally as well with the bell or other shapes of shades. The socket C, is connected to the conductor pipe of tube D, and mounted upon or connected to this pipe or tube D is the inner shell E which may be of any suitable size and shape and constitutes the receiving portion of the socket holder or cover. This inner shell E is preferably provided with threads E' and also with an annular shoulder E². An outer shell F is connected to the inner shell E through the medium of the threads E', and this outer shell is movable upon the inner one for two purposes as will be hereinafter explained.

Shade holding wings or members G are hinged or pivotally connected to the lower end of the inner shell, said hinge or pivotal connection being intermediate the ends of the wings as shown and preferably accomplished by means of lugs E³, projecting through slots G⁴, formed in the wings, said lugs E³ being bent in opposite directions to prevent dislocation. The lower ends of these wings G⁴ are curved or flared outwardly as shown in order to engage the interior of the shade as most clearly shown in Fig. 3, and the upper ends of the wings are formed with

inwardly projecting flanges E^2 , which are adapted to be brought into engagement with the annular shoulder E^2 , when the outer shell F is screwed down thereby locking the wings 5 in their flared or outwardly extending positions and at the same time bearing upon the exterior of the shade at opposing points as most clearly illustrated in Fig. 3, the lip A' of the globe or shade being between the interior supporting wings and the ring of the exterior clamping shell.

In Fig. 2 I have shown two wings G , which are so shaped that when the outer shell is elevated these wings can be collapsed 15 sufficiently to be inserted in the mouth of the globe or shade and after being so inserted these wings can be quickly and easily brought to the positions shown in Fig. 3 and clamped or locked by means of the outer 20 shell F , said outer shell being threaded down upon the inner one as illustrated in Figs. 1 and 3.

In Fig. 5 I have shown three hinged wings and it will of course be understood that any 25 desired number of wings may be employed for the purpose of providing a uniform clamping action upon the interior of the globe or shade.

When it is desired to disconnect the parts 30 the outer shell can be raised so as to free the outer ends of the hinged wings and by collapsing these wings the globe or shade can be quickly and easily withdrawn therefrom.

It will thus be seen that I provide an exceedingly cheap, simple and efficient combination socket and shade cover and holder 35 and which completely eliminates the use of

fastening screws for the purpose of connecting the shade to the socket cover and holder. 40

What I claim is:—

1. A device of the kind described comprising a shell adapted to receive and envelop a socket, means connected to the lower end thereof for engaging the interior of a shade, together with coöperating means attachable to the shell and adapted to engage the exterior of the shade and also hold the interior engaging means in a fixed position. 45

2. A device of the kind described comprising a shell adapted to receive and envelop a socket, wings pivotally connected to the bottom of said shell and adapted to engage the interior of a shade, and an outer shell adapted to engage the exterior of said shell, said outer shell being attachable to the inner shell at a point above the wings and adapted to hold said wings in engagement with the interior of the shade, as set forth. 50

3. A device of the kind described comprising an inner shell adapted to receive and envelop a socket, said shell having a thread thereon, shade holding members pivoted to the lower end of said inner shell, the outer ends of said wings being adapted to engage 60 the interior of a shade, and an outer shell adapted to engage the exterior of said shade, said outer shell having threads adapted to engage the threads upon the inner shell, whereby the wings are held in engagement 65 with the exterior thereof, for the purpose set forth. 70
